UNITED STATES PATENT OFFICE.

JAMES N. CRABB, OF INDIANAPOLIS, INDIANA, ASSIGNOR OF ONE-HALF TO OSCAR J. ENSLEY, OF SAME PLACE.

COIN-TRANSMITTER.

SPECIFICATION forming part of Letters Patent No. 593,800, dated November 16, 1897.

Application filed July 12, 1897. Serial No. 645,300. (No model.)

To all whom it may concern:

Be it known that I, JAMES N. CRABB, of Indianapolis, county of Marion, and State of Indiana, have invented a certain new and useful Coin-Transmitter; and I do hereby declare that the following is a full, clear, and exact description thereof, reference being had to the accompanying drawings, in which like letters refer to like parts.

10 My invention relates to a coin-transmitter or means for carrying coins of different denominations through the mails.

The object of the invention is to provide a device that can be used repeatedly and yet 15 will prevent the escape of the coin without the application of any additional cover, paper, or slip of any kind.

The full nature of my invention will appear from the accompanying drawings and the description and claims following.

In the drawings, Figure 1 is a plan view of the blank out of which my coin-transmitter is made with the parts mucilaged. Fig. 2 is a plan view of the coin-transmitter in completed form.

20 In detail I take a blank piece of stiff paper 1, whose proportions are substantially that shown in Fig. 1, and fold the two sides 4 in toward each other, as shown in Fig. 2, so their 25 adjacent edges will be near together. I apply mucilage, glue, or other similar substance on the inner surface of the sides in strips, as shown at 2 in the drawings, so the distance between them will be but little more than the 30 diameter of a fifty-cent piece. Then the sides are glued down in place, so that between them there will be little pockets or receptacles large enough to receive a fifty-cent piece 35 or smaller coin. I also leave along each edge 40 of the blank short end flaps 3, which are mucilaged also. After the side flaps are secured in place, as above stated, the short end flaps are turned over and down and glued in place 45 over the side flaps for the purpose of binding them down more securely and also of stiffening the device.

In transmitting coin through the mails with this device one inserts the coin in the various receptacles, there being six shown in the 50 drawings—*i. e.*, three on each side. After the coins are inserted the parts of the coin-transmitter bind the coins and hold them in place,

but the coins are further prevented from escaping because the edge of the opposite flap, being directly in front of the opening in the 55 receptacle and near it, serves as an effectual stop or means for preventing the coins from escaping, unless one applies his fingers or bends the paper so that the coin can come out. The coin can be removed by striking the edge 60 of the transmitter against something, so that the coin in the upper half will be partly removed, and then it can be taken out by the fingers. It is seen that this will hold the coins and can be used again and that it is 65 effectual in use.

What I claim as my invention, and desire to secure by Letters Patent, is—

1. A coin-transmitter comprising a main strip or back of stiff material, another strip 70 secured at intervals to the main strip or back to form coin-receptacles, and a strip or stop piece of stiff material secured to the main strip or back near the openings of the coin-receptacles to prevent the escape of the coins 75 therefrom, substantially as set forth.

2. A coin-transmitter comprising a main strip or back of stiff material, and two other strips of stiff material so secured at intervals to the main strip as to form coin-receptacles 80 whose openings are near and opposite to each other, substantially as and for the purpose set forth.

3. A coin-transmitter comprising a single piece of stiff material with two opposite sides 85 folded in toward each other so that their inner edges will be near each other, and with end flaps that are turned down and secure the parts together, substantially as set forth.

4. A coin-transmitter comprising a single 90 piece of stiff material with its opposite sides folded in toward each other so that their inner edges will be near each other, means for securing such sides to the body-piece at intervals so as to form coin-receptacles opening 95 inward, and end flaps that are turned over and secured down upon the side strips, substantially as and for the purpose set forth.

In witness whereof I have hereunto set my hand this 23d day of April, 1897.

JAMES N. CRABB.
